UNITED STATES PATENT OFFICE.

ROY H. HAUGHTON, OF SHREVEPORT, LOUISIANA.

GAME.

Application filed April 7, 1926. Serial No. 100,386.

This invention relates to a game board composed of multiple sections capable of folding one upon the other to enclose the game pieces between the folds of the board. 5 With the above and other objects in view, the invention further includes the following novel features and details of construction, to be hereinafter more fully described, illustrated in the accompanying drawings and 10 pointed out in the appended claims.

In the drawings:

Figure 1 is a plan view of the board as extended for use.

Figure 2 is a perspective of one of the 15 game pieces.

Referring to the drawing in detail wherein like characters of reference denote corresponding parts, the reference characters 10 and 11 indicate individual game boards 20 having a strip 12 adhered or otherwise secured to the inner meeting edges of the boards to permit their folding one upon the other in order that the board may be placed within a confined area, each board having 25 rows of circles inscribed thereon, the outer rows being blank while the inner rows have the configurations of hearts inscribed thereon and each bearing a different numeral reading from left to right. The game 30 pieces, such as indicated at 13, are adapted to be placed over the hearts inscribed upon the inner rows of circles in a manner which will be readily apparent.

The task to be accomplished in the game 35 is to so move and arrange the various men or game pieces on the board that each man will be placed over a heart inscribed upon one of the inner rows of circles and which when positioned the number of which added 40 to the number of the men will equal twenty-five. When every game piece has been so placed the game is won. No man can be moved more than from one circle to the adjacent circle in any direction at one move. The 45 first and last vertical rows are left free and blank to permit of placing game pieces temporarily on those spaces and travelling over them in reaching their destination, and in making room for other men to pass. The 50 point and object is to get all the game pieces placed in the fewest possible moves.

Obviously the board may be made double or single according to the number of persons playing. The boards opposite each 55 other are different in color both in circles, inscribed hearts and game pieces. When

the game is played double two parties play at the same time, each playing his own board, but the plays are made alternately. No racing of moves is allowed and the one 60 who gets all the game pieces placed in the right positions so as to equal the numeral twenty-five first is the winner of the game.

Each board has six rows of circles with six circles in each row and of such dimensions as 65 to fill the board leaving a reasonable margin on the board all around. The circles may be of any color.

The inscribed hearts are enumerated as 70 follows upon one of the game boards:

1—3—5—7
9—11—13—15
17—19—21—23
24—22—20—18
16—14—12—10
8—6—4—2

75

The first and outer vertical rows are left blank without numbers and without inscribed hearts. There are twenty-four heart shaped 80 game pieces of the same color as the inscribed hearts on the board. These men are numbered consecutively one to twenty-four inclusive. Such game pieces are placed on the board in the following order:

1—2—3—4
5—6—7—8
13—14—15—16
17—18—19—20
21—22—23—24

90

The invention is susceptible of various changes in its form, proportions and minor details of construction and the right is herein reserved to make such changes as properly fall within the scope of the appended 95 claims.

Having described the invention what is claimed is:—

1. A game board comprising hingedly secured sections, each section having inscriptions thereon and bearing legends of different values, game pieces adapted for sliding movement upon the faces of the inscriptions and also bearing legends thereon complementary to the legends on the board and which when added thereto are to equal a predetermined number.

2. A game board comprising hingedly secured sections adapted to fold one upon the 110 other, each of the sections having rows of circular portions thereon and having the con-

figuration of objects inscribed thereon and bearing legends of different values, and game pieces of corresponding shape to that of the objects inscribed and also bearing legends complementary to that of the circular portions and which when added thereto are to equal a predetermined numeral.

3. A game board comprising companion sections having a resilient strip secured to the inner meeting edges thereof to permit the sections to fold one upon the other, the pieces of each section having rows of circular portions and including the inscriptions of hearts thereon bearing numerals thereon, substantially heart-shaped game pieces

adapted to be fitted over the heart-shaped inscriptions and also including numerals thereon which when added to a certain enumerated inscription will equal a predetermined number, auxiliary lines of circles arranged upon the outer sides of the aforementioned inscribed circles to facilitate the maneuvering of the heart-shaped game pieces and the inscribed circles in order that the said game pieces may be placed over the inscribed circles to equal the aforementioned numeral. 20 25

In testimony whereof I affix my signature.

ROY H. HAUGHTON.
